UNITED STATES PATENT OFFICE.

ALFRED CONNER, OF EXETER, NEW HAMPSHIRE.

CARRIAGE-SPRING.

SPECIFICATION forming part of Letters Patent No. 259,371, dated June 13, 1882.

Application filed March 13, 1882. (No model.)

To all whom it may concern:

Be it known that I, ALFRED CONNER, of Exeter, in the county of Rockingham, of the State of New Hampshire, have invented a new and useful Improvement in Springs for Wheel-Carriages; and I do hereby declare the same to be described in the following specification and represented in the accompanying drawing, which is a top view of a spring of my improved kind as applied to the axle and perch of a carriage, the body of said carriage being to rest directly on one or a pair of such springs, or indirectly thereon by levers or other proper devices.

The nature of my invention is defined in the claim hereinafter presented.

In the said drawing, A A denote two slides, connected by a flexible band or metallic band-spring, B, arranged between and in line with them, as shown. These slides extend through and slide freely in the cross-heads *a a* of two yokes, C C, one of which is pivoted or hinged, as shown at *b b*, to the axle D, and the other to the front bar, e, of the perch E. Within each yoke, and encompassing its slide A, is a spiral spring, F, which bears against the head *a*, and a washer, e, that rests against a nut, f, screwed on the slide, all being arranged as represented. On the band or spring being pressed downward at its middle the two spiral springs will be contracted, and with the yokes

will move downward, the whole forming an elastic support for the carriage-body.

The said combination of the two yokes, springs, slides, and the band or spring connecting such slides constitutes an excellent substitute for a "thorough-brace" for a stage-coach, and answers also as a useful support for the body of a lighter carriage or pleasure-wagon.

I am aware of the carriage-springs shown in the United States Patent No. 2,484. They differ materially from mine, inasmuch as in one case a rigid rod is used in place of the flexible band or spring B of my invention.

I am also aware of the mode of supporting a carriage-body as shown in the United States Patent No. 98,207, it consisting in spring-bars curved upward near their ends, and there provided with hooks, and also with wires wound about such hooks, all of which differ materially from my invention.

What I claim, therefore, is—

The combination of the flexible band or spring B with the two yokes C, and with the two connection-slides A and two spiral springs, F, arranged within such yokes, as shown and described.

ALFRED CONNER.
